CORE BOX

Application filed June 22, 1932. Serial No. 618,736.

Our invention relates to improvements in core boxes and the like, and particularly to an improved core box particularly adapted for casting internal combustion engine pistons.

It is an important object of our invention to provide an improved and novel core box of this type, which is readily assembled and disassembled before and after casting therewith, and which is very efficient and dependable in use.

It is also an important object of our invention to provide a core box of the type described above which will cast a piston having a lighter weight due to the thinner wall made possible, and which will radiate a greater amount of heat than ordinary pistons because of the peculiar construction thereof.

Other objects and advantages of our invention, will be understood from a reading of the following description in connection with the drawings, wherein for purposes of illustration we have shown a preferred embodiment of our invention.

In the drawings:—

Figure 1 is a general side elevational view of the embodiment.

Figure 2 is a horizontal sectional view taken approximately on the line 2—2 of Figure 1, looking downwardly.

Figure 3 is a sectional elevational view of the inside of one of the core box sections.

Figure 4 is a horizontal sectional view taken approximately on the line 4—4 of Figure 3 looking downwardly.

Figure 5 is a plan view of the bottom of the head of the box.

Fig. 6 is a perspective view of a detail of the construction.

Referring in detail to the drawings, the numeral 5 generally designates the core box which is composed of the sectional body portion 6, the ring 7 and the cap 8.

The body portion 6 is composed of two or more sections, such as the section A and the section B. Each of the sections is semi-circular and has a waist 9 at the lower part thereof extending laterally and concentrically of the semi-circular wall 10.

On a level with the upper end of the

waist 9 an interior horizontal rib 11 projects inwardly. Above this rib 11 and about midway of the height of the wall 10 is another horizontal rib 12. The horizontal rib 12 is formed triangular in cross section, though the cross section thereof is not limited to such formation. Spaced above the horizontal rib 12 is a semi-annular boss 13 which is squared and is several times wider than either the horizontal rib 11 or the horizontal rib 12. 55 On the top of the wall 10 on the level with the upper edge of the boss 13, the upper end of the wall is provided with a removable semi-annulus 14 which is removably secured thereto by any suitable means such as screws. 60 This semi-annulus 14 operates to confine movable members which are to be described below.

Extending from a point slightly above the upper edge of the boss 13 and extending in 70 a vertical plane downwardly is a fin 15 of relatively small cross section, but which is extended considerably radially inwardly.

Centralized upon the horizontal rib 12 and extending outwardly from the inside of the 75 wall 10, that is radially inwardly of the section is a circular enlarged wrist pin opening forming boss 16, which is joined with the lower end portion of the vertical fin 15. Diametrically opposite the fin 15 is another, 80 but much narrower fin 17 which extends to and joins the lower horizontal rib 11. It will be observed that the waist 19 is undercut as indicated at 18 to a point which is almost even with the outside of the wall 10. 85

It will be observed that the section A is provided in the vertical edges of its wall 10 with openings 19, 20 located near the lower end of the edges of the wall, to receive pins 21, 22 projecting from the same locations on 90 the vertical edges of the wall 10 of the section B. When the sections A and B are placed so as to form an annulus in the assembled condition, the pins 21, 22 lodge in the openings 19, 20 aligning the sections and preventing relative rotation thereof. The fit of the pins 21, 22 is such that the sections are readily separable.

In order that the sections may be maintained in the proper assembled relationship, 100

movable members are provided which cooperate with the cap 8 when the ring is in place, to maintain all of the elements of the structure in securely assembled condition. 5 The arrangement provided enables the disassembly of the entire structure by simply lifting the ring 7 upwardly and then lifting the cap 8 from the body portion, whereupon the sections of the body portion are free to 10 be drawn apart.

The sections A and B are each provided with circumferentially spaced slots 23 which are formed vertically through the upper edge of the wall 10 downwardly to a level with the 15 lower horizontal rib 11. As seen in Figure 3 and also in Figure 1, the lower end portion of the slots 23 is curved downwardly and outwardly extended below the level of the upper edge of the rib 11 and through the 20 upper portion of the waist 9.

The semi-annuli 14 are provided with slots which are to be noted in Figure 1 as indicated by the numerals 24. The slots 24 are formed in the lower edge or side of the annuli 14 and register with the upper ends of the long vertical slots 23 in the wall 10 of the sections A and B. It appears preferable to space the slots 23 at equal circumferential distances. This arrangement will bring, in 25 the construction shown, the position of two diametrically opposite slots at the ends of the sections. In order to take care of this, the ends of the sections are each cut away as indicated in Figure 3. Thus, when the sections 30 are placed together the cut-out portions form together, the equivalent of one of the slots 23.

At one side of each slot 23 and slightly spaced therefrom there is disposed a pin 25 40 projected radially from the outside of the wall 10, which carries a pin 26 which extends therefrom into and across the slot 23, whereby to maintain in the slot one of the locking members 27. Each of the locking members 45 27 is provided with a horizontal slot 28 in which the pin 26 is engaged in such a way that the locking member 27 is free to slide radially and rock on the pin 26.

Each of the locking members 27 comprises 50 a comparatively thin bar or sheet of metal having the generally vertically elongated portion 29 which has on its lower outer edge an outward and downward curvate formation 30 which is adapted to protrude from the slot 23 in all positions of the locking members, and act as a handle for manipulating the same. It will be observed that the lower edge 31 of the locking member is outwardly and downwardly curved to conform with the 55 curvature of the bottom 32 of the slot 23, so that the locking member will have a climbing action as it moves inwardly. The upper end of the vertical body portion 29 of each locking member is provided with an inwardly 60 directed finger or nose 33 which has a curved 65

upper edge 34, and a downward and outward angular cam surface 35 at its radially inward end to engage certain portions of the cap 8 for retaining the same when the locking members are maintained in the full inward position by the imposition of the clamping ring 7. 70

The cap 8 is a generally annular disk-like body provided on one side with a suitable handle formation 36 and on its other side 75 with the peculiar formations seen in Figure 5. To begin with, the undersurface of the cap 8 is provided immediately inwardly of the circumferential edge thereof with an outstanding relatively thin cupped flange 37 80 which curvedly merges with a flat floor 38. Spaced inwardly of the cupped flange 37 is another flange 39 which is thicker than the flange 37 and is arranged concentric therewith and somewhat spaced from the center 85 projection 40. The center projection 40 is appropriately tapered or conical. Radiating from the center point 40 to and through the flange 39 is a number of ribs 41 which are circumferentially spaced according to the 90 number and spacing of the circumferentially spaced slots and the fins of the body portion of the device, immediately above which and in alignment with which they are to be disposed when the cap is in place. Extending radially in alignment with each of the ribs 41 there is a groove or slot 42 which extends through the periphery of the cap, and some distance vertically therein. 95

It will be observed that the radial ribs 41 100 are formed at their ends with an angular surface having an angularity opposite to that formed on the radially inward end of the finger formations 33 of the locking members 27. These oppositely angular surfaces are 105 adapted to be engaged and to have a cam and clamping action when opposed and engaged, whereby to securely maintain the cap in its appointed relation to the balance of the structure, before and during a casting operation. 110

It will be noticed that two of the radial ribs, namely, ribs 43 and 44, which are to be aligned with the fins 15 of the sections have 115 downwardly extended portions which are adapted to be aligned with the fins 15. The ends of the radial ribs 43, 44 are not undercut as are the remaining ribs for cooperation with the finger locking members.

With the structure described, the assembling operation is as follows. The sections A 120 and B are brought together, and the pins 21 and 22 seated in the openings 19, 20, the cap 8 is placed within the annuli 14 and seated upon the upper edge of the annular boss 13. Proper centering of the cap is ensured by the 125 use of an appropriate pin and hole arrangement, so that quick and accurate assembly is assured. The upper ends of the locking members 27 are then pushed inwardly until the finger portions thereof engage in the un- 130

dercuts in the radial ribs on the underside of the cap 8 and in the radial slots 42 thereof. The ring 7 is then passed about and down upon the outsides of the sections forming the 5 body portion of the device. This movement of the ring 7 will operate against the upper outer edge portions of the locking members 27 and force them inwardly into clamping and cam engagement with the undercut por- 10 tions of the cap, whereby to bring the cap se- curely into forcible engagement with the parts with which it was engaged. The device is then ready for a casting operation.

In disassembling the same after a casting 15 operation, the ring 7 is simply lifted from its position, so that the upper ends of the locking members may fall radially outwardly out of clamping engagement with the cap 8, and then the cap 8 may be lifted, and this frees 20 the sections A and B so that they may be separated without effort.

It will be observed that the formations given the piston by the interior formations of the inner walls of the sections, provided 25 as they are with ribs and as a result of the vertical slots, the boss 13, and the peculiar formations of the underside of the cap 8, will have a much greater radiating surface than is possessed by pistons of ordinary type, and 30 consequently it will be capable of radiating a larger amount of heat than conventional pistons.

Though we have shown and described herein a preferred embodiment of the invention, it 35 is to be definitely understood that we do not desire to limit the application of the invention thereto, and any change or changes may be made in material and structure and ar- 40 rangement of parts, within the spirit of the invention and the scope of the subjoined claims.

What is claimed is:—

1. A sectional casting or core box comprising a sectional body portion, a cap seatable 45 upon the body portion, cap engaging locking members carried by the body portion, and annular means for maintaining said locking means in cap engaging position and for main- 50 taining the sections of the body portion to- gether.

2. A sectional casting or core box comprising a sectional body portion, a cap seatable upon the body portion, cap engaging locking members carried by the body portion, and 55 annular means for maintaining said locking means in cap engaging position and for main- taining the sections of the body portion to- 60 gether, said body portion being composed of a plurality of arcuate sections.

60 3. A sectional casting or core box comprising a sectional body portion, a cap seatable upon the body portion, cap engaging locking members carried by the body portion, and 65 annular means for maintaining said locking means in cap engaging position and for main-

taining the sections of the body portion to- 70 gether, said body portion being composed of a plurality of arcuate sections, the interior of some of said sections being provided with wrist-pin forming projection means.

In testimony whereof we affix our signa- 75 tures.

MYNARD L. HOLLOWAY.
